UNITED STATES PATENT OFFICE

2,030,064

MINING APPARATUS

Morris P. Holmes, Claremont, N. H., assignor to
Sullivan Machinery Company, a corporation of
Massachusetts

Application December 29, 1932, Serial No. 649,347

81 Claims. (Cl. 262—28)

This invention relates to mining apparatus, and more particularly to improvements in coal mining apparatus of the wheel mounted, track supported and guided, bottom cutting type.

5 An object of this invention is to provide an improved coal mining apparatus. Another object is to provide an improved coal mining apparatus of the wheel mounted, track supported and guided, bottom cutting type. A further object is to 10 provide, in a mining apparatus of the above character, improved adjustable kerf cutting mechanism whereby a kerf may be cut at the level of the mine bottom outside and below the level of the mine trackway and in advance of the track- 15 way, in an improved manner. Yet another object is to provide an improved coal mining apparatus having improved kerf cutter driving and adjusting means. Still another object of this invention is to provide, in a mining apparatus of 20 the above character, an improved tiltable supporting structure for the kerf cutting mechanism whereby the kerf cutter may be adjusted to cut on a rolling or uneven bottom or a pitching coal seam. Still another object of this invention is 25 to provide an improved mining apparatus of the wheel mounted, track supported and guided, bottom cutting type particularly adapted for use in mines having relatively low head room, the improved apparatus having an extremely low compact arrangement of parts whereby the vertical 30 dimensions thereof are reduced to a minimum. These and other objects and advantages of the invention will, however, hereinafter more fully appear.

35 In the accompanying drawings there is shown for purposes of illustration, one form which the invention may assume in practice.

In these drawings,—

Fig. 1 is a plan view of the illustrative embodiment of the improved mining apparatus.

Fig. 2 is a side elevational view of the mining apparatus shown in Fig. 1.

Fig. 3 is an enlarged central, longitudinally extending, vertical sectional view taken substantially on line 3—3 of Fig. 1.

Fig. 4 is a horizontal sectional view taken substantially on line 4—4 of Fig. 3.

Fig. 5 is a longitudinally extending vertical sectional view taken substantially on line 5—5 of Fig. 4.

Fig. 6 is a detail sectional view taken on line 6—6 of Fig. 3.

Fig. 7 is a detail sectional view taken on line 55 7—7 of Fig. 3.

Fig. 8 is a detail sectional view taken on line 8—8 of Fig. 7.

Fig. 9 is an enlarged horizontal sectional view taken substantially on line 9—9 of Fig. 2.

Fig. 10 is a detail sectional view taken substantially on line 10—10 of Figs. 1 and 9.

Fig. 11 is an enlarged plan view of the cutter head shown in Fig. 1, with parts shown in horizontal section to illustrate structural details.

Fig. 12 is a longitudinally extending vertical 10 sectional view taken substantially on line 12—12 of Fig. 11.

Fig. 13 is a detail sectional view taken on line 13—13 of Fig. 12.

Fig. 14 is a detail view of the control rod shown 15 in Fig. 13.

Fig. 15 is a detail sectional view taken on line 15—15 of Fig. 14.

Fig. 16 is a detail sectional view taken on line 16—16 of Fig. 13.

Fig. 17 is a transverse vertical sectional view taken on line 17—17 of Figs. 1 and 3.

Fig. 18 is a detail sectional view taken on line 18—18 of Fig. 17.

Fig. 19 is a detail sectional view taken on line 19—19 of Fig. 18.

Fig. 20 is a detail sectional view taken on line 20—20 of Fig. 19.

Fig. 21 is a horizontal sectional view taken substantially on line 21—21 of Fig. 3, with parts 30 omitted to facilitate illustration.

Fig. 22 is a detail sectional view taken on line 22—22 of Fig. 21.

In this illustrative embodiment of the invention there is shown a coal mining apparatus of 35 the wheel mounted, track supported and guided, bottom cutting type, generally comprising a self-propelled base 1 having mounted thereon improved adjustable kerf cutting mechanism, generally designated 2.

The base 1 is herein in the form of a wheeled truck comprising a low compact truck frame 3 adjustably mounted, in an improved manner as hereinafter described, on truck wheels 4 adapted to run along a usual mine track-

way 5 laid on the mine bottom. Mounted on this truck frame 3 for horizontal swinging movement relative thereto about a vertical axis at 6 is an arm structure 7 overhanging the forward end of the truck and in turn having pivotally mounted thereon at 8 for horizontal swinging movement 45

relative thereto, the improved kerf cutting mechanism 2. Carried on the rear end of the truck frame is a motor 9 having its power shaft 10 operatively connected to the mechanisms for driving

50 55 the cutting mechanism, for swinging the arm 55 relative thereto, the improved kerf cutting mechanism 2. Carried on the rear end of the truck frame is a motor 9 having its power shaft 10 operatively connected to the mechanisms for driving the cutting mechanism, for swinging the arm 55

structure and the cutting mechanism about their respective pivots, for adjusting the elevation of and tilting the cutting mechanism and for driving the truck wheels to propel the apparatus, 5 as hereinafter described.

Now referring to the improved kerf cutting mechanism 2, and more particularly to the improved cutter driving means, it will be noted that connected to and driven by the motor power shaft 10 is an alined shaft 11 suitably journaled at its forward end within a bearing 12 suitably supported within a frame 13 herein formed integral with the truck frame and which constitutes the main frame of the cutting mechanism. Keyed 15 to the forward end of the shaft 11 is a bevel pinion 14 (see Figs. 3 and 4), and this pinion meshes with a large bevel gear 15 keyed to a vertical shaft 16 suitably journaled within the main frame 13 and arranged with its axis coincident with the 20 arm structure pivot. Integral with the gear 15 is a bevel gear 17 meshing with a bevel gear 18 keyed to the rear end of a horizontal shaft 19 herein arranged with its axis extending radially with respect to the pivotal axis of the arm structure 7 and suitably journaled within the arm structure, as shown in Fig. 3. Alined with the shaft 19 and connectible thereto in driving relation therewith, is a shaft 20 likewise suitably journaled within the arm structure 7 and having 25 keyed thereto at its forward end, as shown in Fig. 12, a bevel pinion 21. As shown, the bevel pinion 21 meshes with a large bevel gear 22 keyed at 23 to a tubular drive shaft 24 suitably journaled within the cutter head frame 25 of the cutting mechanism and herein arranged with its axis alined with the pivotal axis 8 of the kerf cutting mechanism. Keyed at 26 to the reduced hub portion 27 of the tubular shaft 24 is a vertical shaft 28 herein formed with longitudinal splineways 29 throughout a substantial portion of its length and splined at 30 to the upper end of, and having telescopically arranged therein, a tubular shaft element 31, which has herein formed integral therewith a chain sprocket 32 which engages and drives a usual endless cutter chain 33 mounted for orbital movement about the margin of a usual elongated plane cutter bar 34. The clutch for connecting the alined shafts 19 and 20 in driving relation, and which herein constitutes 35 the cutter chain clutch, comprises a shiftable clutch member 35 having internal teeth interlocked with clutch teeth 36 formed on the rear end of the shaft 29 and engageable with similar clutch teeth 37 formed on the forward end of the shaft 19. This clutch member is shiftable into its connected or released positions by means of a 40 slidable clutch operating member 38 guided within a longitudinal slot 39 formed within the frame 40 of the arm structure 7. Pivottally connected 45 at 41 to the member 38 is an operating handle 42 having formed thereon a pin 43 engageable with either of two apertures 44 formed in the arm frame 40. This pin and these apertures form a lock for holding the clutch member 35 in either 50 of its two positions. It will thus be evident that the cutter chain 33 may be operatively connected in driving relation with the motor 9 or may remain idle, at will.

The cutter bar 34 is mounted on the cutter head 70 frame 25 for swinging movement therewith about the bar pivot axis 8, and is adjustable into different elevated positions relative to the cutter head, as will now be described. The cutter head 25 is 75 rotatively mounted within bearing sleeves 45, 45 encircling the head and supported by a rigid an-

nular frame 46 rigidly secured to the forward end of the arm frame 40 and constituting the outer overhanging extremity of the arm structure 7. Formed integral with the cutter head frame 25 are laterally projecting guides 47, 47 received in vertical guideways 48, 48 formed on an arcuate frame portion 49 integral with the cutter bar hanger 50. This bar hanger is provided with a bearing portion 51 carrying bearing sleeves 52 interposed between flanges on the shaft 31 and within which the lower end of the latter is journaled, as shown in Fig. 12. These guideways 48 are provided with adjustable bearing plates 53 secured by screws 54 to the guide portions 55 of the hanger frame 49, as shown in Fig. 11. It will 15 thus be seen that the cutter bar 34 is swingable with the cutter head frame 25 relative to the annular frame 46 of the arm structure 7, and that the cutter bar may be adjusted into different elevated positions relative to the cutter head frame 20 by adjustment thereof along the vertical guides 47, 47.

The mechanism for adjusting the cutter bar vertically along the guideways 47, 47 relative to the cutter head frame 25 herein comprises a spur gear 57 rotatably mounted on the tubular shaft 24 and connectible in driving relation with the shaft 24 by a multiple disc clutch 58 of a usual design. Herein arranged parallel with the shaft 24, and likewise suitably journaled within the cutter head frame 25, is a tubular shaft 59 having formed integral therewith at its lower end a nut 60 having internal threads meshing with the external threads of a vertical screw 61. The screw 61 is herein non-rotatable and is pivotally connected at 62 at its lower end to a transverse pin 63 supported at its ends within spaced depending webs 64 integral with the bar hanger support 50. Formed integral with the shaft 59 is a spur gear 65 meshing with a spur gear 66 journaled on a vertical shaft 67 carried by a swingable hanger mounting 68. This hanger mounting is provided with an arcuate guiding portion 69 rotatably mounted within an arcuate bearing portion 70 herein formed integral with the cutter head frame 25, the hanger being mounted to swing horizontally about the axis of the tubular shaft 59. As shown in Fig. 13, the spur gear 66 meshes with a spur gear 71 journaled on a vertical shaft 72 arranged parallel with the shaft 67 and likewise mounted within the swingable hanger mounting 68. When the hanger mounting 68 is in the position as shown in Fig. 13 the spur gears 66, 71 are both out of mesh with the teeth of the spur gear 57, but when the hanger mounting is swung in one direction, the teeth of the gear 66 are brought into mesh with the gear 57, while when the hanger mounting is swung in the opposite direction, the gear 71 is brought into mesh with the gear 57. It will thus be evident that, depending upon the position of the swingable mounting 68, the gear 65, and consequently the nut 60, may be rotated in one direction or the other, thereby to effect adjustment of the cutter bar upwardly or downwardly relative to the cutter head.

The means for applying the clutch 58 and for swinging the mounting 68 for the reversing gears will now be described. As shown in Fig. 11, journaled within the cutter head frame 25 is a longitudinally extending shaft 75 having pivotally mounted thereon at 76 an operating lever 77. The inner end of the shaft 75 is transversely slotted at 78, 78 to receive arms 79, 79 integral with a rotatable operating member 80 herein

arranged surrounding the hub portion 27 of the shaft 24 and supported for rotative movement on the upper operating plate 81 of the clutch 58. Also formed integral with the member 80 is a tooth-like projection 82 fitted within a notch 83 formed on a projection 84 integral with the swingable reverse gear mounting 68. It will thus be seen that when the shaft 75 is moved axially in one direction or the other, the operating member 80 is rotated, thereby shifting the reverse gear mounting 68 in one direction or the other to bring either the gear 66 or the gear 71 in mesh with the drive gear 57. Upon rotative movement of the shaft 75, the sides of the flattened portions 78 act as cams to effect swinging of the operating member 80 downwardly about its fulcrum 85, thereby to apply the disc clutch 58. Means is provided for preventing application of the clutch 58 prior to meshing engagement of one or the other of the gears 66, 71 with the gear 57, and comprises arcuate grooves 86 and 87 formed on the shaft 75 and connected by a longitudinal groove 88. Cooperating with these grooves is a pin 89 secured to the cutter head frame. When the shaft 75 is in the position shown in Fig. 13, rotative movement thereof is prevented by the pin 89 engaging the sides of the longitudinal slot 88. When the shaft 75 is slid either inwardly or outwardly to bring either the gear 66 or the gear 71 in meshing engagement with the drive gear 57, the pin is brought into registry with one or the other of the arcuate grooves 86, 87, thereby permitting rotation of the shaft 75 to effect application of the disc clutch 58.

Now referring to the improved mechanism for swinging the arm and cutter bar about their respective pivots, it will be observed that secured to the vertical shaft 16 above the bevel gear 17 is a worm 90 meshing with and driving in opposite directions worm wheels 91 and 92. These worm wheels are rotatably mounted on parallel shafts 93 and 94, respectively, arranged at opposite sides of the shaft 16 on longitudinally extending axes and spaced equidistantly from the axis of the shaft 16. These worm wheels are connectible to the shafts 93 and 94, respectively, by multiple disc clutches 95 and 96. The shafts 93 and 94 are suitably journaled within the arm frame 40 and are connectible by sliding clutches 97 and 98, respectively, to aligned screw shafts 99 and 100. Threadedly engaging the screws 99 and 100 are trunnion nuts 101 and 102, respectively, mounted within longitudinal guideways 103 formed in the arm frame and pivotally connected at 104 and 105, respectively, to pairs of link members 106 and 107. The link members 106 are pivotally connected at 108 to lateral ears 109 formed integral with the rotatable cutter head frame 25, while the link members 107 are pivotally connected at 110 to a lug 111 formed integral with a frame member 112 secured by screws 113 to the main frame 13. Keyed to the shafts 93 and 94, respectively, are spur gears 114 and 115 meshing with an idler gear 116 suitably rotatably mounted on the rearward portion of the shaft 19. The arm frame 40 is provided with a circular guide flange 117 mounted within an arcuate guideway 118 formed by the frames 13 and 112, and is supported for rotative movement by a bearing sleeve 119. The arm structure 7 is guided during its swinging movement relative to the truck frame, by an arcuate guide 120 integral with the front portion of the truck frame and engaging an arcuate guideway 121 formed on the frame of the arm structure. It will thus be seen that when one or the other of the clutches 95, 96 is applied and the clutch 97 connected, the screw shaft 99 may be rotated in one direction or the other, thereby to swing the cutter bar 34 in either direction about its pivot through the trunnion nut and link connection 101, 106. It will also be seen that when one or the other of the clutches 95, 96 is applied and the clutch 98 is connected, the screw shaft 100 may be rotated in one direction or the other, thereby to effect swinging of the arm structure 7 in either direction through the sliding trunnion nut and link connection 102, 107.

The operating means for the clutch members 97, 98 comprises, as shown in Fig. 10, shipper 15 yokes 125, 126 engageable with grooves formed on the members 97 and 98. These clutch members are mounted on a transverse operating rod 127 slidably and rotatably mounted within the arm frame 40. Pivotedly connected to the opposite ends of the shaft 127 are operating levers 128. The shipper yoke 125 is provided with an arcuate slot 129 and a communicating longitudinal slot 130, while the shipper yoke 126 is provided with similar slots 131 and 132. Projecting 20 within these slots in the shipper yokes 125, 126, respectively, and secured to the shaft 127, are pins 133 and 134. When the pins are in the position shown in Fig. 10, that is, when the shaft 127 is slid outwardly to the left, the shipper yoke 125 is connected to the shaft 127 by the pin 133 received in the longitudinal slot 130, while the shipper yoke 126 is disconnected from the shaft 127 by the arcuate slot 131. When the rod 27 is slid into its opposite position, the shipper yoke 126 is connected to the shaft, while the shipper yoke 125 is disconnected therefrom. When the shaft 127 is in the central position, both pins are engaged within the longitudinal slots, thereby connecting both shipper yokes to the operating shaft. It will thus be seen that the clutches 97, 98 may be independently or simultaneously connected.

Improved variable speed mechanism is provided for controlling the disc clutches 95, 96 so 45 that the arm and bar swinging screws may be operated at a wide range of speeds between zero and a predetermined maximum. This improved clutch controlling means comprises an operating shaft 135 having pivotally connected thereto an 50 operating lever 136, as shown in Figs. 3 and 9. This shaft 135 is threaded at 137 with right and left hand threads, and is threadedly engaged with a split sleeve forming separately adjustable nut elements 138 and 139. Engaging collared portions of these nut elements are levers 140 and 141. As the connections between these pivoted levers 140, 141 and the operating elements 142 for each of the disc clutches 95, 96 are identical, the detailed description of the operating means for the 55 clutch 95 will suffice for both. Rotatable with the gear 91 is a sleeve 143 (see Fig. 21) having formed on its rearward face a cam surface 144 with which engages a sliding member 145 pivotally connected at 146 to the lever 140. Fulfilled at 147 against the forward face of the bearing sleeve 148 for the rearward end of the shaft 93 is a lever 149, and this lever is engageable with the rear face of the outer race of a ball thrust bearing 150 through which pressure 70 is transmitted to the clutch operating member 142 to effect application of the clutch 95. The inner end of the lever 149 is pivotally connected at 151 to the eye of a bolt member 152. This bolt is slidably guided within a sleeve 152a on 75

which is slidably mounted a trunnion 153 pivotally connected at 154 to the lever 140. Encircling the bolt 152 between the bolt head 155 and a washer 156 abutting the rear end of the sleeve 152^a, is a coiled spring 157 which normally urges the bolt eye in engagement with the front end of the sleeve. The bolt 152 is threaded within its eye and is adjustable relative thereto to vary the compression of the spring 157 as desired. The 10 sliding or lost-motion connection between the trunnion 153 and the sleeve 152^a permits adjustment of the lever 140, upon adjustment of the nut 138, without affecting the position of the lever 149, the trunnion sliding on the sleeve 152^a during such adjustment. When the operator rotates the shaft 135 in the proper direction, the 15 control mechanism for the clutch 96 is operated to release its respective clutch, while the control mechanism for the clutch 95 is operated to apply its respective clutch. It will thus be seen that as the cam 144 rotates with the worm wheel 91, the cam acts on the inner end of the slide 145, moving the latter rearwardly and thereby swinging the lever 149 and, through the bolt connection, swinging the lever 149 forwardly against the thrust bearing 150 to effect application of the clutch 95. By adjustment of the screw 137, the lever 140 may be swung either forwardly or rearwardly to vary the position of its pivoting point; and as a result, as the cam 144 rotates, the lever 149 is variably swung, thereby varying the intervals of application of the disc clutch 95. By adjustment of the lever 140 into a position wherein the slide member 145 is held continuously against the surface of the cam, the disc clutch 95 is constantly applied. In other words, movement of the slide member 145 to the left in Fig. 21 will impart a load to the shipper member 142 which will be determined by the extent of movement of the bolt 152 and the degree of compression of the spring 157. More specifically, rotation of the screw 137 in a direction to effect axial movement of the half nut toward the left in Fig. 21, moves the fulcrum of the lever 140 toward the left, and thereby moves the member 145 into engagement with the cam 144; and upon rotation of the cam the lever 140 is swung, thereby moving the bolt 152 to the left to swing the lever 149 to the right, and thereby load the clutch 95. When the half nut is moved to the left so far that the trunnion 153 continuously abuts the washer 156 encircling the bolt 152, continuous application of the clutch 95 will be effected and the spring 157 will compress during each rotation of the cam an amount substantially equal to the full throw of the cam; but since the load of the spring is desirably above the minimum necessary to effect power transmission through the clutch discs, there will be no release even when the slide 145 is in engagement with the lowermost point in the cam. However, by moving the nut graduated amounts toward the right in Fig. 21, the period of drive during each rotation of the cam will be progressively reduced until the clutch is entirely released and drive is discontinued. It will thus be seen that drive of the screws 99 and 100 through the disc clutches may be effected at any desired speed from its maximum speed down to zero, by proper adjustment of the parts. Overloading will be prevented by the presence of the springs 157.

The improved mechanism for effecting truck wheel drive to propel the apparatus along the mine trackway both during cutting and transport, herein comprises a worm 160 (see Fig. 3) formed

integral with the shaft 16 below the bevel gear 15 and meshing with and driving in opposite directions worm wheels 161 and 162. These worm wheels are journaled on parallel longitudinally extending shafts 163, 164, respectively, arranged at the opposite sides of the shaft 16 and in the same longitudinally extending vertical planes as the screw shafts 99 and 100. These worm wheels are connected to the shafts by multiple disc clutches 165, 166, respectively. Keyed to the rear 10 ends of the shafts 163, 164, respectively, are spur gears 167 and 168 meshing with a spur gear 169 journaled on a tubular shaft 170. The shaft 170 surrounds the shaft 11 heretofore described and is clutched at its rearward end at 171 to a worm 15 172 suitably journaled within a gear and axle housing 173. The worm 172 meshes, as shown in Fig. 17, with a worm wheel 174 connectible by a multiple disc clutch 175 to a transverse shaft 176 suitably journaled within the gear housing 20 173. The operating means for the clutch 175 comprises a pressure plate 178 with which engages a ball thrust bearing 179. Engageable with the outer race of the ball thrust bearing is a shipper yoke 180 fixed to an operating shaft 181 suitably 25 journaled within the gear housing 173. Fixed to the shaft 181 is a suitable operating lever 182 (see Fig. 3). Keyed to the shaft 176 and driven thereby is a chain sprocket 183 connected by a chain 184 to a chain sprocket 185 keyed to the 30 rear axle 186 to which the rear truck wheels 4 are secured. Fixed to the opposite ends of the axle 186 are chain sprockets 187, 187 connected by endless chains 188, 188 to chain sprockets 189, 189 secured to the front truck wheels 4, as shown 35 in Fig. 4. Splined to the sleeve 170 is a jaw clutch member 190 having clutch teeth 191 connectible to clutch teeth 192 formed on the gear 169. The clutch member 190 is also provided with clutch teeth 193 connectible to clutch teeth 194 formed 40 on the bevel pinion 14. The clutch member 190 is operated by a shipper yoke 195 fixed to a transverse operating shaft 196 having a suitable operating handle 197. The disc clutches 165, 166 are each provided with a variable speed control mechanism, respectively generally designated 198, 199, 45 whereby the disc clutches may be either constantly or intermittently and variably applied to effect variable speed drive of the shafts 163, 164, and this control mechanism is identical to that 50 above described in connection with the arm and bar swinging screw shafts 99, 100. Therefore, further detailed description of the same is deemed unnecessary. However, in this instance the operating mechanism for the mechanisms 198, 199 55 includes a toothed wheel 200 keyed to the screw operating shaft, and pivotally mounted on the screw operating shaft is a lever 201 carrying a dog 202. This dog is slidably guided at 203 within the lever and is normally held in its released position by a coiled spring 204. Formed at the outer extremity of the lever is a socket 205 for receiving a spherical member 206 formed on an operating rod 207. This operating rod is provided with a suitable handle 208 conveniently located at the 65 side of the truck frame. The spherical member 206 is provided with a cam surface 209 so that when the rod 207 is rotated, the dog 202 is slid downwardly into engagement with the teeth of the member 200. The operator then grasps the 70 handle 208 and pulls the rod 207 outwardly to effect swinging of the lever to thereby rotate the screw operating rod of the control mechanism. The dog 202 may be released by rotating the spherical member 206 to bring the cam surface 75

209 into a position to permit release of the dog. It will thus be seen that the truck wheels may be driven at a high transport speed directly through the shaft 11, bevel pinion 14, clutch 190, sleeve 5 170 and the worm gearing 172, 174, and at a relatively low cutting speed through the worm gearing 160, 161, 162, parallel shafts 163, 164, spur gears 167, 168 meshing with spur gear 169, and in either of opposite directions under the control of the disc clutches 165, 166. The low cutting speed may be varied by regulating the control mechanisms 198, 199 for the disc clutches 165, 166.

As above mentioned, the truck frame is mounted for tilting movement; and to afford such tilting movement, the gear housing 173 is provided with bearing portions 215, 216 mounted within bearing sleeves 217 carried within bearing supports 218, 219 formed, respectively, on the truck frame and the main frame 13, as shown in Fig. 4. This bearing mounting on the gear housing 173 permits rocking movement of the truck frame about a longitudinal axis, i. e. the axis of the shaft 11. The axle housing mounting for the truck frame is also provided with journals 220, 220 within 20 which the rear axle is rotatably mounted, and these journals form a pivotal mounting for the truck frame to enable tilting of the truck frame about a transverse axis, i. e. the axis of the rear axle 186. The improved mechanism for effecting such tilting movement of the truck frame to vary the angle in altitude of the cutting mechanism, herein comprises shafts 221, 222 aligned with the shafts 163, 164, respectively, as shown in Fig. 4 and connectible to the latter shafts by sliding toothed clutch members 223 and 224, respectively. 30 These clutch members are each operated by a shipper yoke 225 secured to a transverse shaft 226 having a suitable operating lever 227. These shafts 221, 222 are suitably journaled within the main frame 13 and have formed thereon screw shafts 228 and 229, and these screw shafts are each connected, as shown in Fig. 5, to a nut 230. Pivotedly connected at 231 to each nut is a link 232, in turn pivotally connected at 233 to an arm 234. These arms are keyed at 235 to aligned shafts 236, 237, respectively, suitably journaled within the truck frame, as shown in Fig. 4. Formed integral with the arms 234 are arms 238 carrying the axles 239, 240, respectively, on which 40 the front truck wheels are journaled. It will thus be seen that when the clutches 223, 224 are connected, the screw shafts 228, 229 may be rotated to effect swinging of the arms, thereby tilting the truck frame upwardly about the axis 55 of the rear truck wheel axle. By releasing one or the other of the clutches 223, 224, one of the arms may be swung while the other is stationary, thereby effecting tilting of the truck frame within its journal 215, 217 about a longitudinal axis. 50 It is accordingly evident that by suitable adjustment of the arms carrying the front truck wheels, the truck frame may be tilted relative to the horizontal, and as a result the angle in altitude of the cutter bar may be varied relative to the horizontal, it being possible to tilt the cutter bar about 60 transverse and longitudinal axes. The drive chains 188, 188 for the front truck wheels are maintained under tension by spring pressed guide plates or shoes 245, 246 slidably engaging the upper and lower runs of the chains and maintained under tension by coiled springs 247, the 70 spring pressed plates 245, 246 maintaining the chains at all times under tension during adjustment of the front tilting arms for the truck 75 frame.

Power is supplied to the motor 9 through a power conductor cable 250 wound upon a cable reel 251 mounted at one side of the truck frame, as shown in Fig. 1. This cable reel is driven to effect winding or unwinding of the power conductor cable as the apparatus moves along the trackway by a pulley 252 keyed to the shaft 176 (see Fig. 17). This pulley is connected by a belt 253 to a pulley 254 keyed to the cable reel driving shaft 255. A suitable adjustable pulley 10 256 engages the upper run of the belt 253 to vary the tension of the belt. Formed internally within the pulley 152 is a braking surface 257 with which a brake band 258 cooperates. This brake band, as shown in Fig. 18, is formed in 15 segments, and these segments are pivotally connected at 259 to adjusting screws 260 connected to abutments 261 formed on the gear housing 173. Secured to the ends of the brake segments are operating elements 262, 262 cooperating to 20 form a conical surface 263 with which a conical operating member 264 cooperates. When the operating member 264 is moved inwardly, the operating elements 262, 262 are separated, thereby forcing the brake segments into braking contact 25 with the brake surface 257. The operating member 264 is actuated by a screw shaft 265 threadedly connected within a trunnion nut 266 carried by the gear housing 173. This shaft is provided with a suitable operating handle 267. The 30 operating lever 182 for the disc clutch 175 of the truck wheel driving mechanism is so arranged that when the truck wheel brake is applied, the disc clutch is always released, and vice versa. As shown in Fig. 19, the clutch operating lever 182 35 is arranged directly in the path of movement of the operating shaft 265 for the brake, so that when the brake is applied, as in the manner shown, the lever 182 is released. When the screw shaft 265 is moved inwardly to effect release of 40 the brake operating element 264, the clutch operating lever 182 is engaged by the shaft and swung outwardly to effect application of the clutch.

The operation of the improved mining apparatus is as follows: The apparatus is propelled 45 along the mine trackway at a high transport speed through the high speed drive mechanism including drive shaft 11, bevel pinion 14, clutch 190, worm gearing 172, 174 and the chain and sprocket connections connected to the truck 50 wheels. The direction of high speed truck wheel drive may be reversed by reversing the motor 9. When the working face is reached, the clutch 98 is connected, and upon application of the disc clutch 96 the screw 100 is rotated, thereby effecting swinging of the arm structure 7 horizontally relative to the truck frame, through the trunnion nut and link connection, from the central position shown in Fig. 1 to a position where-in the bar pivot axis 8 lies outside the trackway. 55 As the arm structure is swung laterally, the clutch 97 may be connected to effect drive of the screw 99, thereby to effect swinging of the cutter bar about its pivot through the trunnion nut and link connection in the opposite direction 60 until the parts assume an angularly related position with the tip end of the cutter bar at the right hand rib of the entry. The bar and arm swinging clutches 97, 98 are then disconnected. The bar elevating nut 60 is then operated by 70 bringing the proper gears 66, 71 in mesh with the spur gear 51, thereby lowering the cutter bar to a position at the level of the mine bottom outside and below the level of the trackway. The clutch 190 is then shifted to connect the spur 75

gear 169 to the sleeve 170, and upon application of the slow speed truck drive controlling clutch 169 and application of the friction clutch 175, the truck wheels are driven to propel the apparatus forwardly along the mine trackway at a low speed to sump the cutter bar beneath the coal. After the completion of the sumping cut, the brake 257, 258 is applied, thereby holding the truck wheels stationary, and the arm and bar swinging screws 99, 100 are then operated to swing the arm and cutter bar in opposite directions about their respective pivots until they assume a straight line position, the bar swinging screw thereafter being disconnected from the motor and the cutter bar swung about the axis 6 of the arm to effect its swinging cut across the coal face in advance of the trackway. When the tip end of the cutter bar reaches the left hand rib, the cutter bar is swung in the opposite direction until the parts assume an angularly related position, the arm and bar swinging mechanisms thereafter being disconnected from their drives. The apparatus is then propelled rearwardly along the mine trackway to effect withdrawal of the cutter bar from beneath the coal. It will be evident that the arm 7 and cutter bar 34 may be independently or simultaneously swung about their respective pivots at variable cutting speeds under the control of the variable speed control mechanism for the disc clutches 55, 96 and that the apparatus may be propelled at a predetermined high transport speed. If it is desired to tilt the cutter bar to vary its angle in altitude during the horizontal cutting operation, this may be accomplished by operating the clutches 223, 224 controlling the tilting screws 228, 229, it being possible to tilt the cutter bar about longitudinal and transverse axes. The cutter bar may be adjusted to cut at different levels simply by operating the elevating screw and nut mechanism 60, 61 to raise or lower the cutter bar.

As a result of this invention, it will be noted that an improved wheel mounted, track supported and guided, bottom cutting type mining apparatus is provided, having improved adjustable cutting mechanism whereby a horizontal kerf may be cut at the level of the mine bottom outside and below the level of the mine trackway and in advance of the trackway. It will further be noted that by the provision of the improved bar adjusting and swinging mechanism, it is possible to swing and adjust the bar in an improved manner. It will still further be noted that by the provision of the improved tilting mechanism for the cutter bar, the cutter bar may be adjusted to cut on uneven or rolling bottom or a pitching coal seam. These and other uses and advantages of the improved mining apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a support, a cutter frame mounted on said support for rotation relative thereto about a vertical axis with the bottom of said frame projecting below the bottom of said support and said frame having depending verti-

cal guides extending downwardly from the upper portion of said support a substantial distance below the bottom of said support, a cutter support mounted on said cutter frame for rotation therewith and adjustable vertically along said guides, a kerf cutter carried by said cutter support, and driving means for said kerf cutter including a cutter driving element arranged with its axis coincident with the axis of rotation of said cutter frame. 10

2. In a mining apparatus, a support, a cutter frame mounted on said support for rotation relative thereto about a vertical axis with the bottom of said frame projecting below the bottom of said support and said frame having depending vertical guides extending downwardly from the upper portion of said support a substantial distance below the bottom of said support, a cutter support mounted on said cutter frame in planes below the bottom of said first support for rotation therewith and adjustable vertically along said guides, a kerf cutter carried by said cutter support and swingable horizontally with said cutter support and frame relative to said first support, and driving means for said kerf cutter including a cutter driving element arranged with its axis coincident with the axis of rotation of said cutter frame. 20

3. In a mining apparatus, a wheeled truck frame having front and rear truck wheels, an arm pivotally mounted on said truck frame for horizontal swinging movement relative thereto about a vertical axis located between the front and rear truck wheel axes, a kerf cutter pivotally mounted on the outer extremity of said arm, and motor operated devices between the truck frame 30 and the front truck wheels and separately or simultaneously adjustable to effect tilting of said truck frame about longitudinal and transverse axes. 35

4. In a mining apparatus, a wheeled truck frame having front and rear truck wheels, kerf cutting mechanism thereon, motor operated devices between the front truck wheels and said truck frame and independently or simultaneously adjustable to effect tilting of the truck frame 45 about longitudinal and transverse axes, and a motor on said truck frame for actuating said kerf cutting mechanism and said tilting devices. 50

5. In a mining apparatus, a portable base, an arm pivotally mounted on and overlying said base and at its outer extremity overhanging said base, a kerf cutter pivotally mounted on said overhanging extremity of said arm, motor operated swinging devices carried by said arm for independently swinging said arm and kerf cutter 55 about their respective axes including rectilinearly guided, movable power swinging devices, one for effecting arm swing and the other for effecting cutter swing and each including a power element movable rectilinearly of its guiding means during the swinging operation. 60

6. In a mining apparatus, a portable base, an arm mounted on and overlying said base and at its outer extremity overhanging said base, a kerf cutter pivotally mounted on said overhanging extremity of said arm, motor operated swinging devices carried by said arm for independently swinging said arm and kerf cutter about their respective axes and including rectilinearly guided, movable power swinging devices, one for effecting arm swing and the other for effecting cutter swing and each including a power element movable rectilinearly of its guiding means during the swinging operation, and a motor carried by said base and 70 75

relative to which said arm is swingable for operating said power swinging devices.

7. In a mining apparatus, a portable base, an arm swingably mounted on and overlying said base and at its forward extremity overhanging said base, a kerf cutter pivotally mounted on the overhanging extremity of said arm, motor operated screw and nut devices for independently swinging said arm and kerf cutter about their respective pivots, and a motor for actuating both of said devices.

8. In a mining apparatus, a portable base, an arm swingably mounted on and overlying said base and at its forward extremity overhanging said base, a kerf cutter pivotally mounted on the overhanging extremity of said arm, motor operated screw and nut devices carried by said arm for independently swinging said arm and kerf cutter about their respective pivots, and a motor for actuating both of said devices.

9. In a mining apparatus, a portable base, an arm swingably mounted on and overlying said base and at its forward extremity overhanging said base, a kerf cutter pivotally mounted on the overhanging extremity of said arm, motor operated screw and nut devices for independently swinging said arm and kerf cutter about their respective pivots, and a motor on said base and relative to which said arm is swingable for actuating said screw and nut devices.

10. In a mining apparatus, a portable base, an arm swingably mounted on and overlying said base and at its forward extremity overhanging said base, a kerf cutter pivotally mounted on the overhanging extremity of said arm, motor operated screw and nut devices carried by said arm for independently swinging said arm and kerf cutter about their respective pivots, and a motor on said base and relative to which said arm is swingable for actuating said screw and nut devices.

11. In a mining apparatus, a portable base, but a single arm mounted on and overlying said base and at its outer extremity overhanging said base, said arm mounted for but confined to horizontal swinging movement relative to said base, a kerf cutter pivotally mounted on the overhanging extremity of said arm and having a support, said arm constituting the sole supporting connection between said base and said kerf cutter support, a motor on said base and relative to which said arm is swingable, and means driven by said motor and including arm and kerf cutter swinging devices mounted on said arm for independently swinging said arm and kerf cutter about their respective pivots.

12. In a mining apparatus, a portable base, but a single arm mounted on and overlying said base and at its outer extremity overhanging said base, said arm mounted for but confined to horizontal swinging movement relative to said base, a kerf cutter pivotally mounted on the overhanging extremity of said arm and adjustable relative to said arm into different elevated positions, said kerf cutter having a support and said arm constituting the sole supporting connection between said base and said cutter support, a motor on said base and relative to which said arm is swingable, means driven by said motor for independently swinging said arm and kerf cutter about their respective pivots, and means driven by said motor for adjusting said kerf cutter into aforesaid elevated positions relative to said arm.

13. In a mining apparatus, a support, a frame

swingably mounted thereon, a kerf cutter pivotally mounted on said frame, and motor operated screw and nut devices for independently swinging said frame and kerf cutter about their respective pivots and common motor operated driving means for said devices.

14. In a mining apparatus, a support, a frame swingably mounted thereon, a kerf cutter pivotally mounted on said frame, and motor operated screw and nut devices carried by said frame for independently swinging said frame and kerf cutter about their respective pivots and common motor operated driving means for said devices.

15. In a mining apparatus, a support, a frame swingably mounted thereon, a kerf cutter pivotally mounted on said frame, motor operated screw and nut devices for independently swinging said frame and kerf cutter about their respective pivots, and a motor on said support and relative to which said frame is swingable for actuating said screw and nut devices.

16. In a mining apparatus, a support, a frame swingably mounted thereon, a kerf cutter pivotally mounted on said frame, motor operated screw and nut devices carried by said frame for independently swinging said frame and kerf cutter about their respective pivots, and a motor on said support and relative to which said frame is swingable for actuating said screw and nut devices.

17. In a mining apparatus, a portable base, a single rigid horizontal arm swingably mounted on and overlying said base and at its outer extremity overhanging said base, said arm confined to horizontal swinging movement relative to said base, a horizontal kerf cutter pivotally mounted on the overhanging extremity of said arm and having a support, said arm constituting the sole supporting connection between said base and said cutter support, a motor on said base and relative to which said arm is swingable for independently swinging said arm and kerf cutter about their respective pivots, and means driven by said motor for tilting said base relative to the horizontal to vary the plane of swinging movement of said arm.

18. In a mining apparatus, a portable base, a single rigid horizontal arm swingably mounted on and overlying said base and at its outer extremity overhanging said base, said arm confined to horizontal swinging movement relative to said base, a kerf cutter pivotally mounted on the overhanging extremity of said arm and adjustable relative to said arm into different elevated positions, said kerf cutter having a support and said arm constituting the sole supporting connection between said base and said cutter support, a motor on said base and relative to which said arm is swingable for independently swinging said arm and kerf cutter about their respective pivots and for adjusting said kerf cutter into aforesaid elevated positions relative to said arm, and means driven by said motor for tilting said base with respect to the horizontal to vary the plane of swinging movement of said arm.

19. In a mining apparatus, a portable base, a single rigid horizontal arm swingably mounted on and overlying said base and at its outer extremity overhanging said base, said arm confined to horizontal swinging movement relative to said base, a horizontal kerf cutter pivotally mounted on the overhanging extremity of said arm and having a support, said arm constituting the sole supporting connection between said base and said arm.

75

cutter support, a motor on said base and relative to which said arm is swingable for independently swinging said arm and kerf cutter about their respective pivots, and devices driven by said motor for actuating said kerf cutter and for tilting said base with respect to the horizontal to vary the plane of swinging movement of said arm.

20. In a mining apparatus, a portable base, a single rigid horizontal arm swingably mounted on 10 and overlying said base and at its outer extremity overhanging said base, said arm confined to horizontal swinging movement relative to said base, a kerf cutter pivotally mounted on the overhanging extremity of said arm and adjustable relative to said arm into different elevated positions, said kerf cutter having a support and said arm constituting the sole supporting connection between said base and said cutter support, a motor on said base and relative to which said arm is 20 swingable for independently swinging said arm and kerf cutter about their respective pivots and for adjusting said kerf cutter into aforesaid elevated positions relative to said arm, and devices driven by said motor for actuating said kerf 25 cutter and for tilting said base with respect to the horizontal to vary the plane of swinging movement of said arm.

21. In a mining apparatus, a portable base, an arm structure pivotally mounted on said base to 30 swing horizontally relative thereto, the forward extremity of said arm structure overhanging the forward end of said base, a cutter frame pivotally mounted on the outer overhanging extremity of said arm structure for rotation about an axis parallel with the arm structure axis and having depending vertical guides extending downwardly in advance of said base, a cutter support mounted on said guides for vertical adjustment therealong and swingable with said cutter frame relative 35 to said arm structure, and a kerf cutter carried by said cutter support, said cutter frame and cutter support being swingable relative to said arm to swing said kerf cutter about the axis of said cutter frame.

45. 22. In a mining apparatus, a portable base, an arm structure pivotally mounted on said base to swing horizontally relative thereto, the forward extremity of said arm structure overhanging the forward end of said base, a cutter frame pivotally 50 mounted on the outer overhanging extremity of said arm structure for rotation about an axis parallel with the arm structure axis and having depending vertical guides extending downwardly in advance of said base, a cutter support mounted 55 on said guides for vertical adjustment therealong and swingable with said cutter frame relative to said arm structure, a kerf cutter carried by said cutter support, said cutter frame and cutter support being swingable relative to said arm 60 to swing said kerf cutter about the axis of said cutter frame, and a motor carried by said base and relative to which said arm structure is swingable for actuating said kerf cutter, for rotating said cutter frame relative to said arm structure 65 and for adjusting said cutter support vertically along said guides.

23. In a mining apparatus, a frame, a swingable arm structure overlying said frame and having at its outer extremity an annular frame portion, a cutter frame rotatably mounted on said arm structure and having top and bottom bearing elements journaled on said annular frame portion, a cutter support carried by said cutter frame beneath the latter, and a kerf cutter carried by 75 said cutter support, said cutter frame and cutter

ter support being swingable about the cutter frame axis to swing said kerf cutter about the cutter frame axis.

24. In a mining apparatus, a swingable arm structure having at its outer extremity an annular portion, a cutter frame rotatably mounted on said arm structure and having top and bottom portions journaled on said annular portion, said cutter frame having depending vertical guides, a cutter support adjustable vertically along said guides relative to said cutter frame, and a kerf cutter carried by said cutter support, said kerf cutter being swingable with said cutter frame and cutter support about the cutter frame axis and adjustable along said guides into different 15 elevated positions.

25. In a mining apparatus, a swingable arm structure having at its outer extremity an annular frame portion, a cutter frame rotatably mounted on said arm structure and having top and bottom bearing elements journaled on said annular frame portion, a cutter support carried by said cutter frame, a kerf cutter carried by said cutter support, said cutter frame and cutter support being swingable about the cutter frame axis to swing 25 said kerf cutter about the cutter frame axis, motor operated means for actuating said kerf cutter including a motor driven shaft journaled on said arm structure, a shaft journaled on said cutter frame and arranged with its axis 30 coincident with the cutter frame axis, gearing connecting said shafts in driving relation and housed within said cutter frame and driving connections between the last mentioned shaft and the kerf cutter, and means driven by said gearing for swinging said cutter frame, cutter support and kerf cutter about the cutter frame axis.

26. In a mining apparatus, a swingable arm structure having at its outer extremity an annular portion, a cutter frame rotatably mounted on 40 said arm structure and having top and bottom portions journaled on said annular portion, said cutter frame having depending vertical guides, a cutter support adjustable vertically along said guides relative to said cutter frame, a kerf cutter 45 carried by said cutter support, said kerf cutter being swingable with said cutter frame and cutter support about the cutter frame axis and adjustable along said guides into different elevated positions, and motor operated devices for actuating 50 said kerf cutter including a motor driven shaft journaled on said arm structure, a telescopic torque shaft journaled on said cutter frame and cutter support and arranged with its axis coincident with the cutter frame axis, gearing connecting said shafts in driving relation and arranged within said cutter frame, and driving connections between said torque shaft and the kerf cutter.

27. In a mining apparatus, a swingable arm 60 structure having at its outer extremity an annular portion, a cutter frame rotatably mounted on said arm structure and having top and bottom portions journaled on said annular portion, said cutter frame having depending vertical guides, 65 a cutter support adjustable vertically along said guides relative to said cutter frame, a kerf cutter carried by said cutter support, said kerf cutter being swingable with said cutter frame and cutter support about the cutter frame axis and adjustable along said guides into different elevated positions, motor operated devices for actuating said 70 kerf cutter including a motor driven shaft journaled on said arm structure, a telescopic torque shaft journaled on said cutter frame and cutter 75

support and arranged with its axis coincident with the cutter frame axis, gearing connecting said shafts in driving relation and arranged within said cutter frame, driving connections between said torque shaft and the kerf cutter, and means for adjusting said cutter support vertically along said guides including adjusting devices driven by said gearing.

28. In a mining apparatus, a swingable arm structure, a cutter frame pivotally mounted on said arm structure for rotation about an axis parallel with the arm structure axis, a cutter support carried by said cutter frame and rotatable with said cutter frame about the cutter frame axis, a kerf cutter carried by said cutter support, motor operated means for actuating the kerf cutter including a motor driven shaft journaled on the arm structure, a shaft journaled on the cutter frame and arranged with its axis coincident with the cutter frame axis, gearing connecting said shafts in driving relation and arranged within the cutter frame and driving connections between said last mentioned shaft and the kerf cutter, and means driven by said gearing for swinging said cutter frame, cutter support and kerf cutter about the cutter frame axis.

29. In a mining apparatus, a swingable arm structure, a cutter frame rotatably mounted on said arm structure about an axis parallel with the arm structure axis, said cutter frame having vertical guides, a cutter support mounted on said cutter frame for adjustment vertically along said guides, a kerf cutter carried by said cutter support, said cutter frame and cutter support being rotatable about the cutter frame axis to swing the kerf cutter about the cutter frame axis, and motor operated devices for actuating the kerf cutter including a motor driven shaft journaled on the arm structure, a telescopic torque shaft journaled on the cutter frame and cutter support and arranged with its axis coincident with the cutter frame axis, gearing connecting said shafts in driving relation and arranged within said cutter frame, and driving connections between said torque shaft and the kerf cutter.

30. In a mining apparatus, a swingable arm structure, a cutter frame rotatably mounted on said arm structure about an axis parallel with the arm structure axis, said cutter frame having vertical guides, a cutter support mounted on said cutter frame for adjustment vertically along said guides, a kerf cutter carried by said cutter support, said cutter frame and cutter support being rotatable about the cutter frame axis to swing the kerf cutter about the cutter frame axis, motor operated devices for actuating the kerf cutter including a motor driven shaft journaled on the arm structure, a telescopic torque shaft journaled on the cutter frame and cutter support and arranged with its axis coincident with the cutter frame axis, gearing connecting said shafts in driving relation and arranged within said cutter frame, driving connections between said torque shaft and the kerf cutter, and means for adjusting said cutter support vertically along said guides including adjusting devices driven by said gearing.

31. In a mining apparatus, a swingable arm structure, a cutter frame rotatably mounted on said arm structure about an axis parallel with the arm structure axis, said cutter frame having vertical guides, a cutter support mounted on said cutter frame for adjustment vertically along said guides, a kerf cutter carried by said cutter support, said cutter frame and cutter support being

rotatable about the cutter frame axis to swing the kerf cutter about the cutter frame axis, motor operated devices for actuating the kerf cutter including a motor driven shaft journaled on the arm structure, a telescopic torque shaft journaled on the cutter frame and cutter support and arranged with its axis coincident with the cutter frame axis, gearing connecting said shafts in driving relation and arranged within said cutter frame, driving connections between said torque shaft and the kerf cutter, and means for adjusting said cutter support vertically along said guides including adjusting devices driven by said gearing, said adjusting devices including a vertical screw connected at its lower end to the cutter support, and a cooperating rotatable nut journaled on said cutter frame.

32. In a mining apparatus, a swingable arm structure, a cutter frame rotatably mounted on said arm structure about an axis parallel with the arm structure axis, said cutter frame having vertical guides, a cutter support mounted on said cutter frame for adjustment vertically along said guides, a kerf cutter carried by said cutter support, said cutter frame and cutter support being rotatable about the cutter frame axis to swing the kerf cutter about the cutter frame axis, motor operated devices for actuating the kerf cutter including a motor driven shaft journaled on the arm structure, a telescopic torque shaft journaled on the cutter frame and cutter support and arranged with its axis coincident with the cutter frame axis, gearing connecting said shafts in driving relation and arranged within said cutter frame, driving connections between said torque shaft and the kerf cutter, and means for adjusting said cutter support vertically along said guides including adjusting devices driven by said gearing, said adjusting devices including a vertical screw connected at its lower end to the cutter support, a cooperating rotatable nut journaled on said cutter frame, and gearing connecting said nut in driving relation with said first mentioned gearing including a gear element formed on the nut, a gear element coaxial with the torque shaft, and gearing meshing with said two last mentioned gear elements.

33. In a mining apparatus, a cutter frame having vertical guides, a cutter support mounted on said guides for adjustment vertically therealong, a kerf cutter carried by said cutter support, motor operated means for actuating the kerf cutter including a rotatable driving member journaled in said cutter frame, a telescopic torque shaft journaled in said cutter frame and cutter support, said torque shaft arranged coaxially with and driven by said driving member, and a driving connection between said torque shaft and said kerf cutter, and means for adjusting said cutter support along said guides relative to said cutter frame including adjusting devices separate and distinct from said torque shaft and having driving means driven by said driving member, said driving means for said adjusting means including a driving member coaxial with and rotatable relative to said first mentioned driving member, a driving connection between said last mentioned driving member and said adjusting devices, and a clutch for connecting said second mentioned driving member to said first mentioned driving member for rotation with the latter.

34. In a mining apparatus, a cutter frame having vertical guides, a cutter support mounted on said guides for adjustment vertically therealong, a kerf cutter carried by said cutter support, mo-

- tor operated means for actuating the kerf cutter including a rotatable driving member journaled in said cutter frame, a telescopic torque shaft journaled in said cutter frame and cutter support, said torque shaft arranged coaxially with and driven by said driving member, and a driving connection between said torque shaft and said kerf cutter, and means for adjusting said cutter support along said guides relative to said cutter frame including adjusting devices separate and distinct from said torque shaft and having driving means driven by said driving member, said adjusting devices including a vertical screw connected at its lower end to the cutter support and a cooperating rotatable nut journaled in said cutter frame, said driving means for said adjusting means including a driving member coaxial with and rotatable relative to said first mentioned driving member, a driving connection between said last mentioned driving member and said adjusting devices, and a clutch for connecting said second mentioned driving member to said first mentioned driving member for rotation with the latter.
35. In a mining apparatus, a cutter frame having vertical guides, a cutter support mounted on said guides for adjustment vertically therealong, a kerf cutter carried by said cutter support, motor operated devices for actuating the kerf cutter including a telescopic torque shaft journaled in said cutter frame and said cutter support, a gear coaxial with said torque shaft for driving the latter, and driving connections between said torque shaft and the kerf cutter, and means for adjusting the cutter support along said guides relative to said cutter frame including adjusting devices driven by said gear, said adjusting devices including a vertical screw connected at its lower end to the cutter support, and a cooperating rotatable nut journaled in said cutter frame and gearing driven by said gear for rotating said nut including a gear coaxial with the torque shaft, a gear formed on said rotatable nut, and gearing meshing with said gears.
36. In a mining apparatus, a cutter frame having vertical guides, a cutter support mounted on said guides for adjustment vertically therealong, a kerf cutter carried by said cutter support, motor operated devices for actuating the kerf cutter including a motor driven shaft journaled in said cutter frame, a telescopic torque shaft journaled in said cutter frame and said cutter support, gearing connecting said shafts in driving relation and driving connections between said torque shaft and the kerf cutter, and means for adjusting said cutter support along said guides relative to said cutter frame including adjusting devices driven by said gearing, the driving connections between said gearing and said adjusting devices including reversing means whereby while said gearing operates continuously in the same direction the adjusting devices may be operated in either of opposite directions.
37. In a mining apparatus, a support, a swingable frame mounted on said support, a cutter frame pivotally mounted on said frame to rotate about an axis parallel with the swingable frame axis, and motor operated devices for swinging said frames about their respective axes including parallel screws journaled on said swingable frame, means for rotating said screws, nuts cooperating with said screws respectively and guided by said swingable frame, and links pivotally connected to said nuts respectively and respectively to said cutter frame and support.

38. In a mining apparatus, a support, a swingable frame adjustably mounted thereon, a cutter frame rotatably mounted on said swingable frame, and means for swinging said frames about their respective axes including parallel guideways formed on said swingable frame, elements reciprocable in said guideways, means for reciprocating said elements, and links pivotally connected to said reciprocable elements respectively and respectively connected to said cutter frame and support.

39. In a mining apparatus, a wheel supported truck frame adapted to run along a mine track-way and having front and rear truck wheels, horizontal kerf cutting mechanism carried by said truck frame, and means for tilting said truck frame about transverse and longitudinal axes relative to a horizontal plane including the truck wheel axes including an axle mounting for the rear truck wheels and with which said truck frame has pivotal connection about a longitudinal axis, separate axle mountings for the front truck wheels, arms pivotally connected to said front axle mountings and swingably mounted on the truck frame about axes offset from the truck wheel axes, and separate adjusting means for independently swinging said arms.

40. In a mining apparatus, a wheel supported truck frame adapted to run along a mine track-way and having front and rear truck wheels, horizontal kerf cutting mechanism carried by said truck frame, and means for tilting said truck frame about transverse and longitudinal axes relative to a horizontal plane including the truck wheel axes including an axle mounting for the rear truck wheels and with which said truck frame has pivotal connection about a longitudinal axis, separate axle mountings for the front truck wheels, arms pivotally connected to said front axle mountings and swingably mounted on the truck frame about axes offset from the truck wheel axes, and separate adjusting means for independently swinging said arms including adjusting devices having relatively reciprocable adjusting elements carried by said truck frame, one adjusting device for actuating each arm.

41. In a mining apparatus, a wheel supported truck frame adapted to run along a mine track-way and having front and rear truck wheels, horizontal kerf cutting mechanism carried by said truck frame, and means for tilting said truck frame about transverse and longitudinal axes relative to a horizontal plane including the truck wheel axes including an axle mounting for the rear truck wheels and with which said truck frame has pivotal connection about a longitudinal axis, separate axle mountings for the front truck wheels, arms pivotally connected to said front axle mountings and swingably mounted on the truck frame about axes offset from the truck wheel axes, and separate adjusting means for independently swinging said arms including adjusting devices carried by said truck frame, one for actuating each arm, said devices each including a rectilinearly movable adjusting element and a cooperating element, an arm swingable with said truck wheel axle mounting arm, and a link connecting said last mentioned arm and said rectilinearly movable element.

42. In a mining apparatus, a wheel supported truck frame adapted to run along a mine track-way and having front and rear truck wheels, horizontal kerf cutting mechanism carried by said truck frame, and means for tilting said truck

frame about transverse and longitudinal axes relative to a horizontal plane including the truck wheel axes including an axle mounting for the rear truck wheels and with which said truck frame has pivotal connection about a longitudinal axis, separate axle mountings for the front truck wheels, said front axle mountings each having independent adjustable mountings on the truck frame, and independent adjusting means for adjusting said front axle mountings.

10 Justing said from this invention:
43. In a mining apparatus, a portable base, an arm structure pivotally mounted on said base to swing horizontally relative thereto about a vertical axis, a kerf cutter pivotally mounted on the
15 outer extremity of said arm structure and adjustable relative thereto, motor operated kerf cutter actuating means including a motor driven shaft journaled on said base, a shaft journaled on said base and arm structure and arranged
20 with its axis coincident with the arm structure pivot axis, gearing connecting said shafts in driving relation, shafting journaled on said arm structure and driven by said gearing, a shaft arranged with its axis coincident with the kerf
25 cutter pivot axis and gearing connecting said shafting and said last mentioned shaft in driving relation, and means driven by said last mentioned gearing for adjusting said kerf cutter relative to said arm structure and including a shaft
30 parallel with said last mentioned shaft.

30 parallel with said last mentioned
44. In a mining apparatus, a portable base, an
arm structure pivotally mounted on said base to
swing horizontally relative thereto about a verti-
cal axis, a kerf cutter pivotally mounted on and
35 adjustable relative to the outer extremity of said
arm structure, and motor operated kerf cutter
actuating means including a motor driven shaft
journaled on said base, a shaft journaled on said
base and arm structure and arranged with its axis
40 coincident with the arm structure pivot axis,
gearing connecting said shafts in driving relation,
shafting journaled on said arm structure and
driven by said gearing, a shaft arranged with its
axis coincident with the kerf cutter pivot axis,
45 gearing connecting said shafting and said last
mentioned shaft in driving relation, means driven
by said second mentioned shaft for swinging said
arm structure relative to said base, and means
driven by said last mentioned gearing for adjust-
ing said kerf cutter relative to said arm structure.
50

30 45. In a mining apparatus, a portable base, an arm structure pivotally mounted on said base to swing horizontally relative thereto about a vertical axis, a kerf cutter pivotally mounted on the 45 outer extremity of said arm structure, and motor operated kerf cutter actuating means including a motor driven shaft journaled on said base, a shaft journaled on said base and arm structure and arranged with its axis coincident with the arm 55 structure pivot axis, gearing connecting said shafts in driving relation, shafting journaled on said arm structure and driven by said gearing, a shaft arranged with its axis coincident with the kerf cutter pivot axis, and gearing connecting 60 said shafting and said last mentioned shaft in driving relation, means driven by said second mentioned shaft for swinging said arm structure relative to said base and for swinging said kerf cutter relative to said arm structure, and means 65 driven by said last mentioned gearing for adjusting said kerf cutter relative to said arm structure. 70

46. In a mining apparatus, a portable base, an arm structure pivotally mounted on said base to swing horizontally relative thereto about a verti-

cal axis, a kerf cutter pivotally mounted on the outer extremity of said arm structure, motor operated kerf cutter actuating means including a motor driven shaft journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in driving relation, and means driven by said second mentioned shaft for tilting said base relative to the horizontal.

47. In a mining apparatus, a portable base, an arm structure pivotally mounted on said base to swing horizontally relative thereto about a vertical axis, a kerf cutter pivotally mounted on the outer extremity of said arm structure, motor operated kerf cutter actuating means including a motor driven shaft journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in driving relation, means driven by said second mentioned shaft for swinging said arm structure relative to said base, and means driven by said second mentioned shaft for tilting said base relative to the horizontal. 20 25 30 35 36

48. In a mining apparatus, a portable base, an arm structure pivotally mounted on said base to swing horizontally relative thereto about a vertical axis, a kerf cutter pivotally mounted on the outer extremity of said arm structure, motor operated kerf cutter actuating means including a motor driven shaft journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in driving relation, means driven by said second mentioned shaft for swinging said arm structure relative to said base and for swinging said kerf cutter relative to said arm structure, and means driven by said second mentioned shaft for tilting said base relative to the horizontal. 40 45 50 55

49. In a mining apparatus, a portable base, an arm structure pivotally mounted on said base to swing horizontally relative thereto about a vertical axis, a kerf cutter pivotally mounted on the outer extremity of said arm structure, motor operated kerf cutter actuating means including a motor driven shaft journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in driving relation, means driven by said last mentioned gearing for adjusting said kerf cutter relative to said arm structure and including a shaft parallel with said last men-

- tioned shaft, and means driven by said first mentioned shaft for propelling said base.
50. In a mining apparatus, a portable base, an arm structure pivotally mounted on said base to swing horizontally relative thereto about a vertical axis, a kerf cutter pivotally mounted on and adjustable relative to the outer extremity of said arm structure, motor operated kerf cutter actuating means including a motor driven shaft 5 journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in driving relation, means driven by said second mentioned shaft for swinging said arm 10 structure relative to said base, means driven by said second mentioned shaft for tilting said base relative to the horizontal, and means driven by said first mentioned shaft for propelling said base.
54. In a mining apparatus, a portable base, an arm structure pivotally mounted on said base to swing horizontally relative thereto about a vertical axis, a kerf cutter pivotally mounted on the outer extremity of said arm structure, motor operated kerf cutter actuating means including a motor driven shaft journaled on said base, a shaft journaled on said base and arm structure and arranged with its axis coincident with the arm structure pivot axis, gearing connecting said shafts in driving relation, shafting journaled on said arm structure and driven by said gearing, a shaft arranged with its axis coincident with the kerf cutter pivot axis, and gearing connecting said shafting and said last mentioned shaft in 15 driving relation, means driven by said second mentioned shaft for swinging said arm structure relative to said base, means driven by said second mentioned shaft for tilting said base relative to the horizontal, and means driven by said first mentioned shaft for propelling said base.
55. In a mining apparatus, a support, a frame swingably mounted thereon, a kerf cutter pivotally mounted on said frame, and motor operated devices for independently swinging said frame and kerf cutter about their respective pivots comprising separate adjusting devices each including relatively rotatable and axially movable mechanically interlocking adjusting elements, said elements being self-locking for holding the frame and kerf cutter in adjusted position.
56. In a mining apparatus, a support, a frame swingably mounted thereon, a kerf cutter pivotally mounted on said frame, and motor operated devices carried by said frame for independently swinging said frame and kerf cutter about their respective pivots comprising separate adjusting devices each including relatively rotatable and axially movable mechanically interlocking adjusting elements, said elements being self-locking for holding the frame and kerf cutter in adjusted position.
57. In a mining apparatus, a support, a frame swingably mounted thereon, a kerf cutter pivotally mounted on said frame about an axis parallel with the frame pivot axis, and motor operated devices for independently swinging said frame and kerf cutter about their respective pivots comprising separate adjusting devices each including cooperating motor actuated adjusting elements having relative axial movement.
58. In a mining apparatus, a support, a frame swingably mounted thereon, a kerf cutter pivotally mounted on said frame, and motor operated devices carried by said frame for independently swinging said frame and kerf cutter about their respective pivots comprising separate adjusting devices each including cooperating motor actu-
- 5 10 15 20 25 30 35 40 45 50 55 60 65 70 75

ated adjusting elements having relative axial movement.

59. In a mining apparatus, a portable base comprising a low compact base frame, but a single rigid horizontal arm swingably arranged in relatively low planes closely adjacent the top of said base frame and confined to horizontal swinging movement relative to the base frame, said arm overlying said base frame and at its forward extremity overhanging the forward end of the base frame, vertical depending guides carried at the outer overhanging extremity of said arm and extending downwardly below the top surface of said arm in advance of said base, a cutter support adjustable vertically along said guides, said arm constituting the sole supporting connection between said cutter support and base, a kerf cutter carried by said cutter support, and a motor carried on said base frame at the rear of said arm 10 and in planes below the top surface of said arm and relative to which said arm is swingable for actuating said kerf cutter and for adjusting said kerf cutter support along said guides.

60. In a mining apparatus, a portable base, a horizontally swingable arm pivotally mounted on and overlying said base and at its forward extremity overhanging said base, a cutter frame mounted on the forward overhanging extremity of said arm for rotation relative thereto about an axis parallel with the arm pivot axis, said cutter frame having depending vertical guides, a cutter support mounted on said cutter frame for rotative movement therewith relative to said arm and for vertical adjustment relative to said cutter frame along said guides, a kerf cutter carried by said cutter support, mechanism for swinging said arm while said cutter frame remains stationary as regards rotative movement about its axis relative to said arm, and mechanism for rotating said cutter frame relative to said arm while the latter remains stationary as regards swinging movement about its pivotal axis relative to said base, said mechanisms being operative to swing simultaneously said arm and cutter frame about their respective pivotal axes.

61. In a mining apparatus, a portable base, a horizontally swingable arm pivotally mounted on and overlying said base and at its forward extremity overhanging said base, a cutter frame mounted on the forward overhanging extremity of said arm for rotation relative thereto about an axis parallel with the arm pivot axis, said cutter frame having depending vertical guides, a cutter support mounted on said cutter frame for rotative movement therewith relative to said arm and for vertical adjustment relative to said cutter frame along said guides, a kerf cutter carried by said cutter support and swingable horizontally with said cutter frame and support about the cutter frame axis relative to said arm, mechanism for swinging said arm while said cutter frame remains stationary as regards rotative movement about its axis relative to said arm, and mechanism for rotating said cutter frame relative to said arm while the latter remains stationary as regards swinging movement about its pivotal axis relative to said base, said mechanisms being operative to swing simultaneously said arm and cutter frame about their respective pivotal axes.

62. In a mining apparatus, a swingable frame, a cutter frame mounted on said frame for rotation relative thereto about a vertical axis and having depending vertical guides extending downwardly from the upper portion of said first

frame, a cutter support mounted on said cutter frame for rotation therewith relative to said first frame and adjustable vertically relative to said cutter frame along said guides, a kerf cutter carried by said cutter support, mechanism for rotating said cutter frame relative to said first frame while the latter remains stationary, mechanism for swinging said first mentioned frame about its pivot while said cutter frame remains stationary as regards rotation relative to said swingable frame, said mechanisms being simultaneously operable to effect simultaneous rotation of said cutter frame and swinging of said swingable frame, and mechanism for adjusting said cutter support vertically along said guides and for actuating said kerf cutter.

63. In a mining apparatus, a swingable frame, a cutter frame mounted on said frame for rotation relative thereto about a vertical axis and having depending vertical guides extending downwardly from the upper portion of said first frame, a cutter support mounted on said cutter frame for rotation therewith relative to said first frame and adjustable vertically relative to said cutter frame along said guides, a kerf cutter carried by said cutter support and swingable horizontally with said cutter support and cutter frame relative to said first frame, mechanism for rotating said cutter frame relative to said first frame while the latter remains stationary, mechanism for swinging said first mentioned frame about its pivot while said cutter frame remains stationary as regards rotation relative to said swingable frame, said mechanisms being simultaneously operable to effect simultaneous rotation of said cutter frame and swinging of said swingable frame, and mechanism for adjusting said cutter support vertically along said guides and for actuating said kerf cutter.

64. In a mining apparatus, a portable base, a horizontally swingable arm pivotally mounted on and overlying said base and at its forward extremity overhanging said base, a cutter frame mounted on the forward overhanging extremity of said arm for rotation relative thereto about an axis parallel with the arm pivot axis and having depending vertical guides, a cutter support mounted on said cutter frame for vertical adjustment along said guides, a kerf cutter carried by said cutter support and having orbitally movable cutting means, the pivotal axis of said cutter frame lying within the orbit of said cutting means, and a motor on said base and relative to which said arm is swingable for actuating said kerf cutter, for swinging said arm, for rotating said cutter frame and for adjusting said cutter support along said guides.

65. In a mining apparatus, a portable base, a horizontally swingable arm pivotally mounted on and overlying said base and at its forward extremity overhanging said base, a cutter frame mounted on the forward overhanging extremity of said arm for rotation relative thereto about an axis parallel with the arm pivot axis and having depending vertical guides, a cutter support mounted on said cutter frame for vertical adjustment along said guides, a kerf cutter carried by said cutter support and having orbitally movable cutting means, the pivotal axis of said cutter frame lying within the orbit of said cutting means, said kerf cutter swingable horizontally with said cutter support and cutter frame about the axis of the latter relative to said arm, and a motor on said base and relative to which said arm is swingable for actuating said kerf cutter, for

- swinging said arm, for rotating said cutter frame and for adjusting said cutter support along its guides.
66. In a mining apparatus, a frame, a cutter frame mounted on said frame for rotation relative thereto about a vertical axis and having depending vertical guides extending downwardly from the upper portion of said first frame, a cutter support mounted on said cutter frame in planes below the bottom of said first frame for rotation with said cutter frame and adjustable vertically relative to said cutter frame along said guides, and a kerf cutter carried by said cutter support and swingable horizontally with said support and cutter frame relative to said first frame, said kerf cutter having orbitally movable cutting means and the pivotal axis of said cutter frame lying within the orbit of said cutting means.
67. In a mining apparatus a wheeled truck frame, kerf cutting mechanism on said truck frame, and motor operated devices between the truck frame and the front truck wheels and separately or simultaneously adjustable to effect tilting of said truck frame about longitudinal and transverse axes to vary the angular cutting position of said kerf cutting mechanism, said adjusting devices for each front truck wheel including a rectilinearly guided, movable element, a connection between said movable element and the truck wheels, and power operated means for moving said element rectilinearly of its guiding means.
68. In a mining apparatus, a portable base, an arm pivotally swingably mounted on and overlying said base and at its forward extremity overhanging said base, a kerf cutter pivotally mounted on the forward overhanging extremity of said arm, motor operated means for independently swinging said arm and kerf cutter about their respective pivots including separate means individual to said arm and kerf cutter and each including a rectilinearly guided, movable element, a connection between said movable element and the element swung thereby and power operated means for moving said element rectilinearly of its guiding means, and a motor on said base and relative to which said arm is swingable for operating said elements.
69. In a mining apparatus, a portable base, an arm pivotally swingably mounted on and overlying said base and at its forward extremity overhanging said base, a kerf cutter pivotally mounted on the forward overhanging extremity of said arm, motor operated means carried by said arm for independently swinging said arm and kerf cutter about their respective pivots and including for said arm and kerf cutter separate adjusting means including for each a rectilinearly guided, movable power swinging device carried by said arm, and a motor on said base relative to which said arm is swingable for operating said power swinging devices.
70. In a mining apparatus, a portable base, an arm pivotally mounted on said base to swing horizontally relative thereto about a vertical axis, a kerf cutter pivotally mounted on the outer extremity of said arm to swing relative thereto about a parallel axis, said kerf cutter being adjustable vertically into different elevated positions with respect to said arm and said arm being tiltable with respect to the horizontal, rectilinearly guided, movable power devices for tilting said arm, rectilinearly guided, movable power devices for swinging said arm and kerf cutter about their respective pivots, a rectilinearly movable power device for adjusting said kerf cutter into different elevated positions with respect to said arm, and a motor on said base and relative to which said arm is swingable for operating said power devices.
71. In a mining apparatus, a frame, a kerf cutter pivotally mounted on said frame, and mechanism for swinging said kerf cutter about its pivot including a screw, a nut threadedly connected to said screw to travel therealong, a link pivotally connecting said nut to said kerf cutter, and motor operated devices for rotating said screw through a wide range of speeds including a driving element coaxial with said screw, a clutch for connecting said driving element in driving relation with said screw, and means actuated by said driving element for automatically intermittently applying and releasing said clutch at varying intervals.
72. In a mining apparatus, a portable base, an arm pivotally mounted on said base to swing horizontally relative thereto, a kerf cutter pivotally mounted on the outer extremity of said arm, and motor operated means for swinging said arm about its pivot through a wide range of speeds including a friction clutch and means for automatically intermittently applying and releasing said clutch, and means for swinging said kerf cutter about its pivot through a wide range of speeds including a friction clutch and means for automatically intermittently applying and releasing said clutch, said arm and kerf cutter swinging means including driving elements coaxial with said clutches respectively and by which said clutch applying and releasing means are respectively actuated.
73. In a mining apparatus, a portable base of relatively low overall height, a horizontal kerf cutter, means for swingably supporting said kerf cutter on said base comprising but a single rigid horizontal arm mounted on and disposed in horizontal planes closely adjacent the top of said base in overlying relation with respect to the latter, said rigid arm at its forward extremity overhanging the forward end of said base and swingable horizontally relative to said base about a vertical axis, said horizontal kerf cutter pivotally mounted on the forward overhanging extremity of said rigid arm, a motor on said base at the rear of said arm and relative to which said arm is swingable for independently swinging said arm and kerf cutter about their respective pivots, said motor disposed within the vertical limits of the apparatus below the top surface of said arm, and means driven by said motor for tilting said base with respect to the horizontal to change the plane of swinging movement of said arm.
74. In a mining apparatus, a portable base of relatively low overall height, a horizontal kerf cutter, means for swingably supporting said kerf cutter on said base comprising but a single rigid horizontal arm mounted on and disposed in horizontal planes closely adjacent the top of said base in overlying relation with respect to the latter, said rigid arm at its forward extremity overhanging the front end of said base and swingable horizontally relative to said base about a vertical axis, said kerf cutter being pivotally mounted on the forward overhanging extremity of said arm and adjustable relative to said arm into different elevated positions between the lower surface of said arm and the mine floor, a motor on said base at the rear of said arm and relative to which said arm is swingable for independently

- 5   swinging said arm and kerf cutter about their respective pivots and for adjusting said kerf cutter into aforesaid elevated positions relative to said arm, said motor disposed within the vertical limits of the apparatus below the top surface of said arm, and means driven by said motor for tilting said base with respect to the horizontal to change the plane of swinging movement of said arm.
- 10   75. In a mining apparatus, a portable base of relatively low overall height, a horizontal kerf cutter, means for swingably supporting said kerf cutter on said base comprising but a single rigid horizontal arm mounted on and disposed in horizontal planes closely adjacent to the top surface of said base, said rigid arm at its forward extremity overhanging the front end of said base and swingable horizontally relative to said base about a vertical axis, said kerf cutter pivotally mounted on the forward overhanging extremity of said arm, a motor on said base at the rear of said arm and relative to which said arm is swingable for independently swinging said arm and kerf cutter about their respective pivots, said motor disposed within the vertical limits of the apparatus below the top surface of said arm, and devices driven by said motor for actuating said kerf cutter and for tilting said base with respect to the horizontal to change the plane of swinging movement of said arm.
- 15   76. In a mining apparatus, a portable base of relatively low overall height, a kerf cutter, means for swingably supporting said kerf cutter on said base comprising but a single rigid horizontal arm mounted on and disposed in horizontal planes closely adjacent to the top surface of said base in overlying relation with respect to the latter, said rigid arm at its forward extremity overhanging the forward end of said base and swingable horizontally relative to said base about a vertical axis, said kerf cutter pivotally mounted on the forward overhanging extremity of said arm and adjustable relative to said arm into different elevated positions between the bottom of said arm and the mine floor, a motor on said base at the rear of said arm and relative to which said arm is swingable for independently swinging said arm and kerf cutter about their respective pivots and for adjusting said kerf cutter into aforesaid elevated positions relative to said arm, said motor disposed within the vertical limits of the apparatus below the top surface of said arm, and devices driven by said motor for actuating said kerf cutter and for tilting said base with respect to the horizontal to change the plane of swinging movement of said arm.
- 20   77. In a mining apparatus, a portable base of relatively low overall height, a horizontal kerf cutter, means for swingably supporting said kerf cutter on said base comprising but a single rigid horizontal arm mounted on and disposed in horizontal planes closely adjacent to the top surface of said base in overlying relation with respect to the latter, said rigid arm at its forward extremity having depending vertical guides extending downwardly in advance of said base and overhanging the forward end of said base and swingable horizontally relative to said base about a vertical axis, the forward overhanging extremity of said arm having depending vertical guides extending downwardly in advance of said base and disposed below the top surface of said arm, a cutter support adjustable vertically along said guides between the bottom surface of said arm and the mine floor, said kerf cutter carried by said cutter support and swingable with said support horizontally relative to said arm about an axis parallel with the arm pivot axis, a motor on said base at the rear of said arm and relative to which said arm is swingable for independently swinging said arm and kerf cutter about their respective pivots, said motor arranged within the vertical limits of the apparatus below the top surface of said arm, and means driven by said motor for tilting said base with respect to the horizontal to change the plane of swinging movement of said arm.
- 25   78. In a mining apparatus, a portable base of relatively low overall height and mounted for tilting movement about a longitudinal axis, a horizontal arm pivotally mounted on said base to swing horizontally relative thereto about a vertical axis and arranged in horizontal planes closely adjacent to the top surface of said base, the forward extremity of said arm overhanging the forward end of said base, depending vertical guides carried by the forward overhanging extremity of said arm and extending downwardly in advance of said base below the top surface of said arm, a cutter support mounted on said guides below the bottom surface of said arm for vertical adjustment therealong between the bottom surface of said arm and the mine floor, a kerf cutter carried by said cutter support, said kerf cutter swingable horizontally relative to said arm in any adjusted position of said cutter support along said guides about an axis parallel to the arm pivot axis, and a motor on said base and relative to which said arm is swingable for swinging said arm and kerf cutter and for adjusting said cutter support, said motor arranged with its longitudinal axis coincident with the axis of tilting of said base.
- 30   79. In a mining apparatus, a portable base of relatively low overall height and mounted for tilting movement with respect to the horizontal, a horizontal arm pivotally mounted on said base to swing horizontally relative thereto about a vertical axis and arranged in horizontal planes closely adjacent to the top surface of said base, the forward extremity of said arm overhanging the forward end of said base, depending vertical guides carried by the forward overhanging extremity of said arm and extending downwardly in advance of said base below the top surface of said arm, a cutter support mounted on said guides below the bottom surface of said arm for vertical adjustment therealong between the bottom surface of said arm and the mine floor, a kerf cutter carried by said cutter support, said kerf cutter swingable horizontally relative to said arm, in any adjusted position of said cutter support along said guides, about an axis parallel to the arm pivot axis, a motor carried by said base at the rear of said arm and relative to which said arm is horizontally swingable for actuating said kerf cutter, for adjusting said cutter support vertically along said guides and for swinging said kerf cutter about its pivot relative to said arm, and means driven by said motor for tilting said base with respect to the horizontal to change the plane of swinging movement of said arm.
- 35   80. In a mining apparatus, a frame, vertical depending guides carried by said frame, a cutter support adjustable vertically along said guides and having guides slidable in said guides, a kerf cutter carried by said cutter support, said depending guides when said cutter is in its uppermost raised position projecting downwardly below the bottom surface of said cutter, motor operated means for driving said kerf cutter including a driving element on said frame, a driven
- 40   5   10   15   20   25   30   35   40   45   50   55   60   65   70   75

element on said cutter support, and a telescopic torque shaft connecting said elements in driving relation and arranged on an axis parallel with said guides at the rear of a transverse vertical plane including said guides, and motor operated means for adjusting said support vertically along said guides including a driving element journaled on said frame, and a cooperating relatively movable adjusting element connected to said cutter support and arranged with its axis parallel with the torque shaft in advance of said transverse vertical plane.

81. In a mining apparatus, a portable base comprising a low compact base frame, but a single rigid horizontal arm arranged in relatively low planes closely adjacent the top of said base frame and confined to horizontal swinging move-

ment relative to the base frame, said arm overlying said base frame and at its forward extremity overhanging the forward end of the base frame, vertical depending guideways carried at the outer overhanging extremity of said arm and extending downwardly below the top surface of said arm in advance of said base, a cutter support adjustable vertically along said guideways, said arm constituting the sole supporting connection between said cutter support and base, a kerf cutter carried by said cutter support, and a motor carried on said base frame at the rear of said arm and in planes below the top surface of said arm and relative to which said arm is swingable, for actuating said kerf cutter.

15. MORRIS P. HOLMES.

CERTIFICATE OF CORRECTION.

Patent No. 2,030,064.

February 11, 1936.

MORRIS P. HOLMES.

It is hereby certified that error appears in the printed specification of the above numbered patent requiring correction as follows: Page 2, second column, line 31, for the numeral "69" read 59; and line 37, for "is" read its; page 6, first column, line 23, after "The" insert the words brake 257,258 is then released and the; page 10, second column, line 7, claim 38, for "guideways" read guideways; page 14, first column, line 20, claim 67, after "apparatus" insert a comma; and that the said Letters Patent should be read with these corrections therein that the same may conform to the record of the case in the Patent Office.

Signed and sealed this 31st day of March, A. D. 1936.

Leslie Frazer
Acting Commissioner of Patents.
